UNITED STATES PATENT OFFICE.

ALDEN E. OSBORN, OF NEW YORK, N. Y.

INTERNAL-COMBUSTION ENGINE.

1,390,810.

Specification of Letters Patent. Patented Sept. 13, 1921.

Application filed August 7, 1917. Serial No. 184,793.

To all whom it may concern:

Be it known that I, ALDEN E. OSBORN, a citizen of the United States of America, and a resident of New York, Bronx county, 5 and State of New York, have invented certain new and useful Improvements in Internal-Combustion Engines, of which the following is a specification, reference being had to the accompanying drawings, forming 10 a part thereof.

My invention relates to internal combustion engines, and has special reference to engines of the sleeve valve type.

One object of my invention is to provide 15 an engine having a simple and reliable valve mechanism that shall possess the advantages incident to the use of a large inlet port located near the outer end of the piston stroke, and at the same time avoid the disadvantages 20 resulting from the production of a relatively high vacuum during that part of the suction stroke before this port is opened.

Another object is to provide against leakage of gas from the cylinder into the main 25 inlet port, by arranging a sleeve passage and relation of the sleeve movement to the movement of the piston, in such a way that the passage through the sleeve is not only below the inlet port in the cylinder at each 30 alternate outward stroke of the piston, but is below the top of the engine piston as well giving a double sealing effect against the leakage of the gas into the inlet port.

A further object is to provide an engine 35 having intake ports of relatively large area at widely distributed points in the engine cylinder.

In order that my invention may be thoroughly understood I will now proceed to 40 describe the same in the following specification, and then point out the novel features thereof in appended claims.

Referring to the drawings:

Figure 1 is a sectional elevation through 45 one of the cylinders and the crank case, of an internal combustion engine, arranged and constructed in accordance with my invention, and constituting an embodiment thereof, the parts being shown in the positions 50 occupied at the end of the working stroke.

Fig. 2 is a view corresponding to Fig. 1, of a slightly modified structure which also embodies my invention, the parts in this case being shown in the positions occupied 55 at the end of the suction stroke.

The piston and sleeve valve are the same in both modifications and the two figures may be considered together as showing the parts in different positions corresponding respectively to the ends of the working and 60 suction strokes as above indicated.

Like parts are designated by the same reference characters in both the figures.

Engines embodying my invention may of course be made with one or more cylinders, 65 but only one is illustrated and this will be sufficient to make the construction and operation clear.

10 designates the cylinder of the engine having an exhaust port 11 and an inlet port 70 12, both of which ports are shown as crossed by suitable bridges for connecting the adjacent parts of the cylinder together. Within the cylinder is a sleeve valve 13 having an exhaust passage 14, and an intake passage 75 15, which passages are also both crossed by connecting bridges between the adjacent parts of the sleeve. Within the sleeve valve operates the piston 16 which is attached by a connecting rod 17 to a crank shaft 19. 80 This is operatively connected by a pinion 20 and gear 21 to the valve crank shaft 22 which runs at one-half the speed of the crank shaft 19.

The sleeve 13 has a projection 23 at the 85 lower end which is operatively connected to the valve crank shaft 22 by a connecting rod 24.

26 designates the crank case, 27 the cylinder head, 28 the intake manifold, and 29 90 the carbureter.

The head 27 has a cooling chamber 30 and extends into the end of the cylinder 10 and into the sleeve 13 in a well known manner. The head is provided with a spark plug 31 95 and has an inlet port 32 controlled by a puppet valve 33. This valve in the structure of Fig. 1, is held on its seat by a spring 34 except when it is opened by the suction produced by the movement of the engine 100 piston.

The manifold 28 has a branch 35 which forms a passage to the inlet port 32, the body of the manifold being directly connected to an intake passage 36 which communicates with an annular chamber 37 and opens into the cylinder through a port 12 105 of large area and the passage 15 in the sleeve 13.

In the arrangement of Fig. 1, the puppet 110

valve 33 operates automatically but this is not essential to my invention and it may be actuated as shown in Fig. 2 by a lever 40 which is pivoted at 41 and is in turn actuated by a rod 42. This rod has an enlargement 43 at its lower end which is actuated by a cam projection 44 on the valve crank shaft 22.

Considering first the engine shown in Fig. 10, 1, if it is assumed that the engine is operating, the parts being shown at the end of the working stroke, with the sleeve passages 15 below the top of the piston, the next half revolution of the crank shaft which 15 corresponds to the exhaust stroke, produces a quarter revolution of the valve crank shaft, the arrangement being such that the burnt gases are forced out through the exhaust port 11 which is finally shut at or 20 near the end of the stroke.

During the next half revolution of the crank shaft 19 which corresponds to the suction stroke, the sleeve valve 13 is moved still farther in an inward direction bringing the parts into the position shown in Fig. 2, at the end of the stroke with the passage 14 well above the exhaust port 11. During the first part of the stroke the intake port 12 and the passage 15 are covered 30 by the piston so that a partial vacuum is produced in the cylinder and the valve 33 is automatically opened in opposition to the spring 34.

When the main inlet port 12 is uncovered 35 the pressure is equalized by the admission of more explosive mixture and the valve 33 closed by the spring 34.

The arrangement thus provides for the admission of fuel at widely separated points 40 in the cylinder, viz., in the cylinder head and near the outer end of the piston stroke.

Attention is directed to the fact that the spring 34 need not be made very strong even if the motor is to operate at high 45 speeds because the inlet opening near the end of the stroke is large and quickly equalizes the pressure and permits the valve to shut. However, if it is found desirable to utilize a stronger spring, it is not necessary 50 to depend on the suction of the engine piston and some suitable actuating mechanism may be utilized such, as, for example, that shown in Fig. 2.

With this arrangement the cam projection 44 actuates the valve 33 during each suction stroke of the engine before the main 55 inlet port 12 is opened.

Attention is also directed to the fact that the sleeve valve and the inlet valve 33 in 60 the arrangement of Fig. 2 are both controlled and actuated by the valve crank shaft 22.

It will be noticed that by having the inlet port 12 and exhaust port 11 extend practically around the entire circumference of

the cylinder (except for bridges where needed) an exceedingly quick opening large port area for the passage of the gas is provided, thus reducing the power loss and heating of the parts through wire drawing 70 of the gas which occurs with small slow opening ports and making warping or burning of the parts less likely than where heating is more localized at one side because of the ports being less symmetrically arranged. 75 It is obvious, however, that the circumferential arrangement of the ports is not essential to the operation of my invention and that one or both ports may be arranged to enter the cylinder at one side only if desired. 80

Other structural modifications may be effected within the spirit and scope of my invention, and I intend only such limitations as are imposed by the appended claims. 85

What I claim is:

1. An internal combustion engine comprising a cylinder, a reciprocating piston therein, an inlet port in said cylinder near the outer end of the piston's stroke, a cylinder head having an inlet port, a valve for the cylinder head port, and a reciprocating valve for controlling the inlet port near the end of the piston's stroke, operatively connected with the piston whereby it is moved 90 over one extreme of its travel during the compression stroke of the piston, over the other extreme of its travel during the exhaust stroke of the piston and through the intermediate parts of its travel during the 95 suction and power strokes of the piston.

2. An internal combustion engine comprising a cylinder, a reciprocating piston, a main inlet and an exhaust port in said cylinder, a sleeve valve for controlling said 105 ports, a piston adapted to cooperate with the sleeve valve in opening said main inlet port, a cylinder head having an auxiliary inlet port adapted to be opened in advance of the main inlet port, means for controlling 110 the opening and closing of said auxiliary inlet port independently of the sleeve valve, and means for operating said sleeve valve from the piston to cause the sleeve valve to move over one extreme of its travel during the compression stroke of the piston, to move over the other extreme of its travel during the exhaust stroke of the piston and to pass through the intermediate parts of its travel 115 during the suction and power strokes of the piston.

3. An internal combustion engine comprising a cylinder having a main inlet and an exhaust port, a sleeve valve for controlling said ports, a cylinder head having an auxiliary inlet valve independent of the sleeve valve adapted to open early in the suction stroke, a spring for closing said auxiliary valve and means for operatively connecting the sleeve and piston to cause the 120

sleeve to pass over one extreme of its travel during the compression stroke of the piston, to pass over the other extreme of its travel during the exhaust stroke of the piston 5 ton and to pass through the intermediate parts of its travel during the suction and power strokes of the piston.

4. An internal combustion engine comprising a piston, a cylinder in which said piston operates and provided with an inlet port disposed near the outer end of the piston stroke, a sleeve valve controlling said inlet port and operatively connected with the piston, a second inlet port disposed in 10 the head of the cylinder, a valve independent of the sleeve valve controlling said inlet port in the head of the cylinder and operating to relieve the partial vacuum in back of the piston on the suction stroke 15 prior to the uncovering of the inlet port at the outer end of the piston stroke, and an inlet manifold branched to supply charges to both the valved inlet port at the outer end of the piston stroke and the 20 separately valved inlet port in the head of the cylinder.

5. An internal combustion engine comprising a cylinder having a main inlet port near the outer end of the piston stroke, a 30 cylinder head having an inlet valve, a spring for closing the inlet valve in the cylinder head, a sleeve valve, and a piston adapted to coöperate with the sleeve valve for controlling said main inlet port and operatively connected with the sleeve valve to cause said 35 sleeve valve to move over one extreme of its travel during the compression stroke of the piston, to move over the other extreme of its travel during the exhaust stroke of the piston 40 ton and to move through the intermediate parts of its travel during the suction and power strokes of the piston.

6. An internal combustion engine comprising a cylinder having a main inlet and 45 an exhaust port, a sleeve valve for controlling said ports, a piston, a cylinder head having an auxiliary valve, means for opening said valve early in the suction stroke and means for operatively connecting the 50 sleeve and piston to cause the sleeve to pass over one extreme of its travel during the compression stroke of the piston, to pass over the other extreme of its travel during the exhaust stroke of the piston and to pass 55 through the intermediate parts of its travel during the suction and power strokes of the piston.

7. An internal combustion engine comprising a cylinder having a main inlet and an 60 exhaust port, a sleeve valve for controlling said ports, a cylinder head having an auxiliary inlet valve and adapted to open early in the suction stroke, means for closing the valve near the end of the suction 65 stroke, a piston, and means for operatively

connecting the sleeve and piston to cause the sleeve to pass over one extreme of its travel during the compression stroke of the piston, to pass over the other extreme of its travel during the exhaust stroke of the 70 piston and to pass through the intermediate parts of its travel during the suction and power strokes of the piston.

8. An internal combustion engine comprising a cylinder having a pair of widely 75 separated inlet ports, a sleeve valve for controlling one of said ports, a puppet valve for controlling the other port, and a single valve crank shaft arranged to actuate both the sleeve and puppet valve so that the sleeve 80 is caused to pass over one extreme of its travel during the compression stroke of the piston, to pass over the other extreme of its travel during the exhaust stroke of the piston and to pass through the intermediate 85 parts of its travel during the suction and power strokes of the piston so that the puppet valve is opened during the suction stroke of the piston.

9. An internal combustion engine comprising a piston, a cylinder having an inlet port near each end of the piston stroke, a puppet valve adapted to close the port near one end of the cylinder, a spring for holding the puppet valve on its seat, a sleeve 95 valve for controlling in conjunction with the piston, the inlet port near the opposite end of the cylinder, a valve crank shaft operatively connected to actuate the sleeve valve to cause said sleeve to pass over one 100 extreme of its travel during the compression stroke of the piston, to pass over the other extreme of its travel during the exhaust stroke of the piston and to pass through the intermediate parts of its travel during 105 the suction and power strokes of the piston, and a cam on the valve crank shaft operatively connected to the puppet valve whereby the puppet valve is opened during 110 the suction stroke of the piston.

10. An internal combustion engine comprising a cylinder, a piston therein, a crank shaft actuated by the motion of said piston, a main inlet port entering the cylinder through the side thereof, an auxiliary inlet port, and an exhaust port, a fuel inlet member communicating with both of said inlet ports, a reciprocatory main valve for controlling the opening and closing of both the main inlet port and the exhaust port, means for actuating said main valve from said crank shaft to cause said valve to pass over one extreme of its travel during the compression stroke of the piston, to pass over the other extreme of its travel during 115 the exhaust stroke of the piston and to pass through the intermediate parts of its travel during the suction and power strokes of the piston, and an auxiliary inlet valve operating independently of the main valve for 120 125 130

controlling the opening and closing of the auxiliary inlet port.

11. An internal combustion engine comprising a cylinder, a piston therein, a crank shaft actuated by the motion of said piston, a main inlet port entering the cylinder through the side thereof, an auxiliary inlet port, and an exhaust port, a reciprocable main valve for controlling the opening and 10 closing of both the main inlet port and the exhaust port, means for actuating said main valve from said crank shaft to cause said valve to pass over one extreme of its travel during the compression stroke of the piston, 15 to pass over the other extreme of its travel during the exhaust stroke of the piston and to pass through the intermediate parts of its travel during the suction and power strokes of the piston, and an auxiliary inlet 20 valve operating independently of the main valve for controlling the opening and closing of the auxiliary inlet port.

12. An internal combustion engine comprising a piston, a cylinder in which said 25 piston operates provided with an inlet port disposed near the end of the outward stroke of the piston and a second inlet port disposed in the end of the cylinder, a sleeve valve controlling one of said inlet ports and 30 operatively connected with the piston, and a second valve controlling the other inlet port independently of the sleeve valve.

13. An internal combustion engine comprising a cylinder, a piston therein, a sleeve 35 valve between the cylinder and piston, a cylinder head provided with a passage opening into the cylinder and with a port in said passage, an independent valve controlling said port, an inlet port in the cylinder 40 controlled by the piston and sleeve valve for admitting an additional charge into the cylinder substantially at the termination of the outward stroke of the piston, an exhaust port in the cylinder, and an exhaust port in 45 the sleeve for controlling said cylinder exhaust port.

14. An internal combustion engine comprising a piston, a cylinder constructed with a single opening through its wall near the 50 inner end of the piston stroke and an inlet port near the outer end of the piston stroke, a sleeve valve in said cylinder and between said cylinder and said piston, an admission valve independent of the said sleeve valve, 55 said sleeve valve being arranged to be moved over and to close said single opening in the cylinder wall during the compression and power strokes of the piston, and an inlet port in the sleeve adapted to coöperate with 60 the inlet port in the cylinder and being covered by the said piston at the end of the exhaust stroke and above the said piston at the end of the suction stroke.

15. An internal combustion engine comprising a piston, a cylinder having an ex- 65

haust port near the inner end of the piston's stroke and an inlet port near the outer end of the piston's stroke, a sleeve valve in said cylinder and between said cylinder and the said piston, an inverted head extending 70 within the sleeve valve at the inner end thereof, an admission valve in the cylinder head independent of the sleeve, an exhaust port near the inner end of the sleeve adapted to coöperate with the exhaust port in the 75 cylinder and being lapped by said cylinder head during the compression and power strokes of the piston, and an inlet port in sleeve adapted to coöperate with the inlet port in the cylinder and being covered by 80 said piston at the end of the exhaust stroke and above said piston at the end of the suction stroke.

16. An internal combustion engine comprising a cylinder, a piston therein, a sleeve 85 valve between the cylinder and piston, a cylinder head extending into said sleeve, said cylinder head being constructed to form a passage into the cylinder, a hollow circumferential chamber between said passage 90 and the exterior of said head adjacent to said sleeve and adapted to contain a cooling medium, a port at the inner end of said passage, an independent valve for controlling the opening and closing of said port to 95 admit explosive charge into said passage at each alternate outward stroke of the piston, means within said passage for igniting the combustible charge in the passage, an inlet port in the cylinder controlled by said 100 piston and said sleeve through which an additional charge is admitted into the cylinder at the termination of each of said alternate outward strokes of the piston, an exhaust port in the cylinder, and an exhaust 105 port in the sleeve adapted to coöperate with the exhaust port and to be lapped by said cylinder head during the compression and power strokes of the piston whereby the leakage of the gases from the combustion 110 chamber to said cylinder exhaust port can only occur through the passage of these gases by the inner end of said head between said head and said sleeve.

17. An internal combustion engine comprising a cylinder provided with an inlet port in the side thereof, a crank shaft, a reciprocating piston, a connecting rod having a bearing on said crank shaft and on said piston, a member geared to said crank 115 shaft to revolve at one-half the speed thereof and having an eccentric portion thereon, a reciprocating sleeve valve controlling the cylinder inlet port, a second connecting rod having a bearing on said eccentric portion 120 of said member and on said sleeve valve and an intake valve in the head of the cylinder independent of the sleeve valve controlled 125 inlet.

18. An internal combustion engine com- 130

- prising a cylinder, a combustion chamber at one end of said cylinder, a valve adjacent said combustion chamber to control the admission of a part of the explosive charge to 5 said chamber, a sleeve valve within the cylinder, a reciprocatory piston within the sleeve valve, an exhaust passage through the wall of said cylinder adjacent to said combustion chamber, a second passage through 10 the wall of said cylinder adjacent the outer end of the piston stroke, an inlet port in said sleeve valve also adjacent to the outer end of said piston stroke and means for mechanically connecting said piston and said sleeve 15 valve, whereby the sleeve valve is moved outwardly in said cylinder to open the ex- haust passage in the cylinder wall and to also bring its inlet port farther out of said cylinder than a point reached by the head of the piston when the piston is at the end of 20 one of its outward strokes, whereby the sleeve valve is moved into the cylinder to close the said exhaust passage and to open its inlet port into the cylinder by the said piston's head over-running said port as the 25 piston reaches the end of its next outward stroke and whereby the sleeve valve is moved past the innermost point of its stroke during the succeeding inward stroke of the piston.

In witness whereof, I have hereunto set 30
my hand this 26 day of July, 1917.

ALDEN E. OSBORN.
